US0D1079891S

(12) **United States Design Patent** (10) **Patent No.:** **US D1,079,891 S**
(45) **Date of Patent:** **** Jun. 17, 2025**

(54) **WATER FILTER CARTRIDGE**

(71) Applicant: **SHENZHEN UAH TECHNOLOGY CO., LTD**, Guangdong (CN)

(72) Inventors: **Shengbo Lu**, Guangdong (CN); **Qiang Geng**, Guangdong (CN); **Shen Tian**, Guangdong (CN); **Weixin Luo**, Guangdong (CN); **Biting Wen**, Guangdong (CN)

(73) Assignee: **SHENZHEN UAH TECHNOLOGY CO., LTD**, Shenzhen (CN)

(**) Term: **15 Years**

(21) Appl. No.: **29/923,138**

(22) Filed: **Dec. 28, 2023**

(30) **Foreign Application Priority Data**

Dec. 22, 2023 (CN) 202330847287.1

(57) **CLAIM**

The ornamental design for a water filter cartridge as shown and described.

DESCRIPTION

FIG. 1 is a bottom, front and left side perspective view of a water filter cartridge showing our new design;

FIG. 2 is a top, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the water filter cartridge which form no part of the claimed design.

1 Claim, 8 Drawing Sheets
